LEMUEL E. HOWARD, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed April 23, 1924. Serial No. 708,408.

My invention relates to railway traffic controlling apparatus, and particularly to apparatus of the type comprising governing mechanism located on a train and controlled 5 from the trackway.

In apparatus of this character it has been customary to provide a low speed limit under unsafe traffic conditions, whereby after entering the unsafe zone the train may proceed without an automatic brake application provided its speed does not exceed such limit. As a further element of safety it has been suggested that while proceeding through the unsafe zone the engineer should be required 15 to perform a manual acknowledging act in order to give evidence of the fact that he is cognizant of the condition under which he is traveling, the penalty for failure to properly perform such act being an automatic 20 brake application even if the speed of the train is below the given low value.

One feature of my invention is the provision of a novel and improved means for requiring such acknowledgment on the part 25 of the engineer.

I will describe one form of apparatus embodying my invention, and will then point out the novel features thereof in claims.

The accompanying drawing is a diagrammatic view showing one form of apparatus 30 embodying my invention.

Referring to the drawing, the reference characters 15 and 15^a, designate the track rails of a railway along which traffic normally moves in the direction indicated by the arrow. These rails are divided by insulated joints 16 into a plurality of track sections, of which only one complete section A-B is shown in the drawing.

Each track section is provided with a track circuit comprising a source of current connected across the rails at one end of the section and a track relay connected across the rails at the other end of the section. In 45 the form here shown, the source of track circuit current is a battery D, and the track relay is of the direct current type designated by the reference character K with an exponent corresponding to the location.

Each section is also provided with a trackway signal designated by the reference character S with an exponent corresponding to the location, each of which signals is controlled by the track relays in the usual man-

ner, so that the signal indicates "proceed," 55 "caution" or "stop," according to traffic conditions in advance of the signal. The control of these signals by the track relays forms no part of my present invention, and so the controlling circuits are omitted from the drawing to simplify the disclosure.

Means are provided for supplying an alternating train governing current to the rails of each track section, which current is furnished by a generator G connected with a transmission line H. This train governing current is applied to the track rails by a transformer designated by the reference character E with an exponent corresponding to the location, the secondary of which transformer is connected in the track circuit between one terminal of the track battery D and one of the track rails. The primary circuit for each transformer is controlled by a front contact 20 of the track relay K for the 70 section next in advance, such primary circuit including the secondary of a line transformer F the primary of which is connected across the transmission line H. It will be seen, therefore, that alternating train governing current is applied to the track rails 80 of each section except the section in the rear of an occupied section.

Located in the section immediately to the left of point A is a train L, which is provided with a circuit a adapted to receive alternating energy inductively from the track rails 15 and 15^a. In the form here shown, this circuit includes two pick-up coils 18, 18^a wound respectively on two magnetizable 85 cores 17, 17^a which are disposed above, and transversely with relation to, the two rails 15 and 15^a. The energy thus induced in the receiving circuit a is employed to control a train-carried relay R in such manner that 90 this relay R is energized when the train occupies a section of track which is supplied with alternating train governing current, but is de-energized when the train occupies a section of track which is not supplied with 95 such current. Preferably an amplifier 19 is interposed between the receiving circuit a and the main relay R.

The train L is also provided with a magnet M controlling a valve V in a brake 105 governing pipe 2, in such manner that de-energization of the magnet M causes an automatic application of the brakes. When

the relay R is energized, magnet M is energized by a circuit which passes from terminal B of a suitable source of current through contact 4 of relay R, wires 5 and 6 winding of magnet M, and wire 7 to terminal O of the same source of current. When relay R is energized, therefore, the train is free to proceed at any speed without incurring an automatic application of the brakes, although if desired means may be interposed in the circuit just traced for magnet M whereby this magnet will be de-energized if the train exceeds a given high speed even though relay R is energized.

15 Also located on the train is a centrifugal device C operated by a gear wheel 3, which in turn is connected by gearing with a wheel of the train. This centrifugal device C controls a contact 13 in such manner that the contact is open at speeds above a safe low value, such as 15 miles per hour, and is closed if the speed does not exceed such value.

20 The train is also provided with a circuit controller T which is biased to the open position by suitable means such as a spring 11, but may be held closed by the engineer by means of a knob 10. In order to keep this circuit controller closed the engineer must 25 keep his hand continuously on the knob 10.

25 The brake controlling magnet M is provided with an auxiliary circuit which passes from terminal B of the said source of current, through back contact 8 of relay R, wire 9, circuit controller T, wire 12, contact 13, wires 14 and 6, magnet M, and wire 7 to terminal O of the same source of current. It will be seen that this auxiliary circuit 30 is closed when relay R is de-energized, provided that circuit controller T is closed and the speed of the train does not exceed the safe low value.

35 As shown in the drawing, the track section immediately to the right of point B is occupied by a second train L^X, so that signal S^B indicates "stop" and signal S^A indicates "caution". The circuit a on the first train L is receiving train governing current from the track rails so that relay R is energized, with the result that the brake controlling magnet M is also energized through its main circuit controlled by front contact 4 of relay R. When the train L enters section A-B, the supply of train governing current to its receiving circuit a will be discontinued because contact 20 of track relay K^B is open, and so the main relay R on train L will become de-energized. If the speed of the train does not exceed 15 miles 50 per hour and the engineer closes circuit controller T, the auxiliary circuit for brake magnet M will be closed, and so the train can proceed without an automatic application of the brakes. If the speed of the train at any instant exceeds 15 miles per

hour, contact 13 will open, so that the brakes will be applied and the train will be brought to a stop. Furthermore, if the engineer releases circuit controller T while relay R is de-energized, the brakes will be applied and the train will be brought to a stop.

Although I have herein shown and described only one form of apparatus embodying my invention, it is understood that various changes and modifications may be made therein within the scope of the appended claims without departing from the spirit and scope of my invention.

Having thus described my invention, what I claim is:

1. Railway traffic controlling apparatus comprising automatic mechanism carried on a train and operating under unsafe traffic conditions to apply the brakes, and means located on the train for preventing an automatic brake application if the speed does not exceed a given value and if and only if the engineer takes suitable continuous action as long as the train proceeds under unsafe traffic conditions.

2. Railway traffic controlling apparatus comprising automatic mechanism carried on a train and effective continuously while the train is traveling under unsafe traffic conditions to apply the brakes, a circuit controller on the train biased to the open position and requiring continuous manual action to keep it closed, and means controlled by said circuit controller for preventing an automatic brake application if and only if the circuit controller is kept closed continuously while the train is traveling under unsafe traffic conditions.

3. Railway traffic controlling apparatus comprising automatic mechanism carried on a train and operating under unsafe traffic conditions to apply the brakes, a circuit controller on the train biased to the open position and requiring continuous manual action to keep it closed, and means for preventing a brake application by said automatic mechanism if the speed is below a given value and if and only if said circuit controller is kept closed continuously while the train is traveling under unsafe traffic conditions.

4. In combination, a train carried relay controlled from the trackway and arranged to be energized or de-energized according as traffic conditions in advance are safe or unsafe, a brake controlling magnet controlled by said relay and energized when said relay is energized, a circuit controller on the train biased to the open position and requiring continuous manual action to keep it closed, and a circuit for said magnet controlled by said circuit controller and by a back contact of said relay and capable of keeping the magnet energized if and only if the circuit

controller is continuously held closed by manual operation as long as the relay is de-energized.

5. In combination, a train carried relay controlled from the trackway and arranged to be energized or de-energized according as traffic conditions in advance are safe or unsafe, a brake controlling magnet governed by said relay and normally de-energized 10 when the relay is de-energized, a circuit controller on the train biased to the open position and requiring continuous manual action to keep it closed, and means operating when said relay is de-energized to keep said magnet energized if and only if said circuit controller is continuously kept closed and if the speed of the train does not exceed a given 15 value.

6. In combination, a train carried relay 20 controlled from the trackway and arranged to be energized or de-energized according as traffic conditions in advance are safe or unsafe, a brake controlling magnet governed by said relay and normally de-energized 25 when the relay is de-energized, and means located on the train for keeping said magnet energized while said relay is de-energized if the speed does not exceed a given value and if and only if the engineer takes 30 suitable continuous action.

7. Railway traffic controlling apparatus

comprising means for supplying train governing current to the track rails under safe traffic conditions in advance and for discontinuing the supply of such current under 35 unsafe traffic conditions in advance, automatic train carried mechanism controlled by said train governing current for applying the brakes in the absence of said current, and means located on the train for preventing 40 operation of said automatic mechanism in the absence of said train governing current if and only if the engineer takes suitable continuous action.

8. Railway traffic controlling apparatus 45 comprising means for supplying train governing current to the track rails under safe traffic conditions in advance and for discontinuing the supply of such current under unsafe traffic conditions in advance, automatic 50 train carried mechanism controlled by said train governing current for applying the brakes in the absence of said current, and means located on the train for preventing operation of said automatic mechanism in 55 the absence of said train governing current if and only if the engineer takes suitable continuous action and the speed of the train does not exceed a given value.

In testimony whereof I affix my signature.

LEMUEL F. HOWARD.

DISCLAIMER

1,604,556.—*Lemuel F. Howard*, Edgewood Borough, Pa. RAILWAY-TRAFFIC-CONTROLLING APPARATUS. Patent dated October 26, 1926. Disclaimer filed June 22, 1933, by the assignee, *The Union Switch & Signal Company*.

Hereby enters the following disclaimer, to wit:
